REINFORCEMENT SUPPORTING CHAIR

Herman G. Keseling, Cuero, Tex.

Application January 16, 1933, Serial No. 652,040

1 Claim. (Cl. 94—8)

This invention relates to improvements in chairs used to support metal reenforcement at the desired height above the ground in the construction of concrete highways and the like.

5 An object of the present invention is to provide an improved reenforcement supporting chair of the above kind having a lateral tongue forming a stop for engagement with the ground to determine the height of the bar holding part 10 of the chair above the ground surface.

A further object of the invention is to provide a one-piece sheet metal chair structure which is extremely rigid in construction and of such simple form as to provide for ready and economical manufacture.

15 A further object is to provide a one-piece sheet metal chair structure having a pointed lower end to enter the ground, and provided with a seat at its upper end to receive a horizontally disposed reenforcing bar, provision being made whereby the chair may receive hammer blows at its upper end, whereby the chair may be readily driven into the ground without danger of destruction or serious damage thereof.

20 25 A still further object is to generally improve chairs for holding and supporting reenforcing bars in the construction of concrete highways and the like.

Other objects and advantages of the invention 30 will become apparent from the following description when considered in connection with the accompanying drawing, in which:

35 Figure 1 is an edge elevational view of a reenforcement supporting chair constructed in accordance with the present invention and operatively supporting a reenforcing bar.

Figure 2 is a side elevational view looking toward the left of Figure 1; and

40 Figure 3 is a perspective view of the chair shown in Figures 1 and 2.

Referring more in detail to the drawing, the present invention relates to a device for supporting a reenforcing bar 5 a predetermined distance from the ground surface 6 so that it will be embedded in the concrete to be subsequently poured 45 to the desired thickness.

The present bar supporting chair consists of a one-piece sheet metal structure of channel form from end to end including a web portion 7 and 50 side flanges 8. As shown, the chair preferably has a relatively narrow slightly tapered and pointed lower end portion 9 to readily enter the ground, a wider upper portion 10 of uniform width, and a relatively abruptly tapered intermediate portion 55 11 connecting the portions 9 and 10.

Struck from the web part of the chair inter-

mediate its ends is a lateral tongue 12 adapted to contact with the ground when the pointed lower end portion 9 is driven into the ground, so as to serve as a stop for determining the height of the upper end of the bar supporting chair from the ground surface. 5

At the upper end of the chair, the web part 7 is provided with a semi-circular notch or recess 13 forming a concaved seat for reception of the reenforcing bar 5. The notch or recess 13 is of 10 a location and size so as to leave a portion of the web part 7 remaining as at 14 at one side of the recess 13 which, in conjunction with the adjacent upper end portion of the adjacent side flange 8 provides an angular prong of very rigid 15 form adapted to receive the blows of a hammer for driving the chair into the ground, without danger of seriously distorting or damaging the chair so that the latter may be re-used many times and maintained in good condition. The 20 side flange 8 at the side opposite the prong 15 is provided at its upper end with an extension 16 which is normally co-extensive with the adjacent portion of said side flange 8 as shown in Figure 3 and indicated by dotted lines in Figure 2. After 25 the bar 5 has been seated in the recess 13, the extension 16 may be readily bent downwardly and inwardly over the top of the bar 5 so as to effectively hold the latter in place within the seat or recess 13, as shown by full lines in Figures 30 1 and 2. Due to the abruptly tapered intermediate portion 11, the major portion of which enters the ground, a wide bearing or purchase is had in the ground to resist swaying of the chair laterally of the bar 5, while tongue 12 resists to a great extent lateral movement of the chair in a direction longitudinally of bar 5.

From the foregoing description, it will be seen that I have provided a reenforcement bar supporting chair which is extremely simple and durable in construction, efficient in use, and capable of being quickly placed in position and secured to the reenforcing bar.

What I claim as new is:

A supporting chair for reenforcing bars comprising a pointed ground-penetrating stake of channel shape in cross section from end to end and having a segmental recess in the upper end of its web portion forming a concaved seat to snugly receive the lower portion of the reenforcing bar, the flange of the chair at one side of said recess having an elongated extension at its upper end adapted to be bent downwardly and inwardly over the exposed upper portion of the reenforcing bar to secure the latter in said seat. 55

HERMAN G. KESELING.
